HIGH TENSION SWITCH PLANT

Filed March 3, 1928.

UNITED STATES PATENT OFFICE

HANS BARTHELT, OF BERLIN-WILMERSDORF, GERMANY, ASSIGNOR TO WESTINGHOUSE ELECTRIC & MANUFACTURING COMPANY, OF NEW YORK, N. Y., A CORPORATION

HIGH-TENSION SWITCH PLANT

Application filed March 3, 1928, Serial No. 258,806, and in Germany March 5, 1927.

My invention relates to a high-tension switchplant.

The employment of high voltages (over 100 kv.) for the transmission of electric power over long distances increased naturally the dimensions of the necessary switchgear, since, as well known, the required flash-over distances between live parts and to ground increase rapidly with increasing voltages. The buildings in which such switchgear is accommodated thus attain sizes which demand very large floor spaces and this increases the first cost of the plant considerably. In order to reduce the cost of such switch-houses, it has been suggested to construct such switchplants as outdoor stations i. e. to mount the switchgear in the open air without enclosing walls. The ground area and space requirement of such a switchplant is, however, not reduced, because the switching equipment is exposed to rain and snow and it is necessary to locate the individual parts at considerably greater distances apart than in a closed building, if the same flash-over safety is to be maintained. Such outdoor plants thus demand a still larger ground area, than the switchgear located in closed rooms. Such large ground spaces are frequently not available, for instance in the case of the switchplant of water-power stations erected in mountainous country, or can only be acquired at great cost in large cities at the other end of a long distance transmission line. For this reason it has already been proposed to place switchplants, such as sub-stations, underground under streets and roads.

According to my invention the ground area and cubic space demand of a high-tension switchplant may be considerably reduced by placing the entire switchgear or switching equipment (busbars, disconnecting switches, transformers, oil circuit breakers, current and potential transformers) into an oiltight vessel or vessels constructed of concrete and filled with oil. In this way the distances necessary between the individual parts of the switchgear may be considerably reduced and the plant be made more compact. The costs for constructing such vessels or tanks of concrete are low compared with other structures

for housing switchgear, since the concrete vessels or tanks may be produced directly in the ground by casting the concrete in a manner well known in the art and the constituents of the switchgear may be conveniently mounted on the concrete walls. 55

It is already known to construct the oil tanks of oil circuit-breakers of concrete, the underlying idea being to obtain a rugged tank capable of withstanding the pressure developed in the event of an explosion within the breaker. This is therefore merely a measure to increase the strength of an oil tank. To render the porous concrete impervious to oil it has also been proposed to cover it with a coat of oilproof paint or to provide it with a suitable protective lining. 60 65

The object of my invention is primarily to reduce the ground area and cubic space requirement of the total switchplant to make the plant more compact and thus to effect a considerable saving in ground space. 70

In a preferred embodiment of my invention the vessel constructed of concrete serving for the reception of the entire switchplant or a plurality of such vessels containing the individual systems of the switchplant is or are subdivided into separate compartments or chambers by insulating partition walls. For the subdivision the same viewpoints are decisive as for the high-tension switchplants in air, such as separating the phases. The insulating partition walls subdividing the entire switchplant into individual compartments are so placed, that they are located behind the disconnecting switches or isolating links branching the individual systems off the busbars or the incoming cables from the generator, so that the switchgear located in the individual compartments is dead when the disconnecting switch is open. This is of particular advantage when repairs have to be made on individual switchgear. 75 80 85 90

The partition walls are preferably constructed in the manner of bulkheads, well known in the art of ship-building, so that the oil is able to circulate normally through all the chambers, but can be drained out of any individual chamber when the bulkheads are closed, so that any individual chamber may 100

be isolated for repairing the switchgear contained in it. For this purpose auxiliary vessels or receptacles are provided in the vicinity of or adjacent to the concrete main vessels, which are in communication with the main oil vessels by pipes. The oil is drawn into these auxiliary vessels when a compartment of the main vessel is drained and forced back again when the compartment is to be filled again with oil. This arrangement has the advantage that the compartment in which the switchgear is contained need not be equipped with such pressure or suction apparatus and the parts of the switching installation are kept free from strains connected therewith.

To prevent a switch compartment from being drained while carrying current a stop valve is provided in the connecting pipe of the main vessel with the auxiliary vessel or at the vessels themselves. This valve is furnished with an interlocking mechanism which allows of it being opened only when the disconnecting switch for the particular compartment at the busbars has been opened.

In order that the complete switching installation may permanently be kept immersed in the oil, provisions may be made that the oil level is continuously or periodically controlled and automatically brought to the prescribed height by an oil pump, should it have dropped.

It is a well known fact, that insulating oil greedily absorbs moisture from the air, particularly when the oil level presents a large surface to the air. This absorption of moisture reduces the dielectric strength of the oil very rapidly and must therefore be prevented as far as possible. I avoid the absorption by covering the entire switching installation or the individual switching compartments, these enclosures being along their edges sealed against the entrance of air by troughs containing a liquid into which the edges dip. These covers may be designed as roller tops and below them there may be provided a web of fine-meshed wire gauze, which when the covers are opened prevent solid particles from dropping into the insulating oil. These covers may in known manner be so interlocked that they can be opened only when the switchgear contained in the respective compartment is dead.

In order to enable the insulating oil to be purified and to keep its dielectric properties under constant supervision, means may be provided to circulate the oil from the compartments by a system of pipes to a purifying plant, where it is purified and returned to the switch compartments.

The switchplant is constructed in the usual manner, so that any portion of the gear is accessible after the draining of the oil for repairs, for instance from a stage. The oil circuit breakers existing in the usual installa-

tion are, with their usual metal tanks, placed into the oil in order to prevent the pressures developed in such breakers, when opening, from being transmitted to the other parts of the switchgear. If such a pressure limitation is considered unnecessary, the oil circuit-breakers may be placed into the concrete vessels without metal containers, for instance, by placing them on the bottom of the vessel where the highest pressure prevails. The 70 transformers, current and potential transformers, extinguisher coils and other oil-filled apparatus also require no longer metal enclosures. My improved design of switch station thus does away with all oil containers 80 and the leading in and out bushings and consequently also with their oil circulating apparatus. The apparatus is connected up by means of simple terminals.

A travelling crane for hoisting the various parts of the switch gear out of the oil vessel may be provided above the entire switch plant and a light roof may cover the entire station. The incoming and outgoing cables pass through suitable bushings into the surrounding atmosphere.

The drawing affixed hereto and forming part of my specification is a vertical section and illustrates diagrammatically a high-tension switching installation according to my invention.

Referring to the single figure of the drawing, 1 is the underground vessel, tank, reservoir, cistern or pit constructed of concrete and subdivided into separate compartments by insulating partition walls 2. In the compartments there are, for instance, located the oil circuit-breakers 3 and above them upon special horizontal partition walls 4 the disconnecting switches 5 placed between the bushbars 6 and the oil circuit-breakers 3. The insulating partition walls 2 and 4 are preferably designed as bulkheads, as customary in ship-building, so that under normal conditions the oil is able to traverse all the compartments, but after closing the openings 7 by the sliding doors 8 each compartment may be drained separately and without affecting the others. In the immediate vicinity of the concrete tank there are provided auxiliary vessels 9, one of which is shown, which communicate with the concrete vessels or tanks by pipes 10. In the connecting pipes 10 between the main and auxiliary vessels there are interposed stop valves 11, provided with locking devices which permit the opening of the stop valves 11 only, when the disconnecting switches or isolating links 5 are open and the switchgear appertaining to them is therefore dead. A pump 19 driven by a motor 20 is provided for each conduit 10, whereby the oil within the various compartments may be pumped therefrom into its respective auxiliary vessel and whereby the oil level in each compartment may be controlled.

To prevent the oil from absorbing moisture from the air, the concrete tanks are, for instance, closed by a roller top 12 against contact with the air. These roller tops seal the 5 tank against the entrance of air by dipping with their edges into troughs or gutters 13 filled with a liquid. Foreign substances are prevented from falling into the tank by a fine mesh wire screen 18 supported on the walls 10 and vertical partitions of the tank. The whole switch station is swept by a travelling and elevating crane 14 for hoisting the individual apparatus out of the tank. A light roof structure 15 covers the entire switching 15 installation. 16 are the incoming and outgoing cables of the switchplant which pass through the bushings 17 and are connected to the overhead transmission line.

Various modifications and changes may be 20 made without departing from the spirit and the scope of the invention, and I desire, therefore, that only such limitations shall be placed thereon as are imposed by the prior art.

I claim as my invention:

- 25 1. High-tension switch plant comprising a circuit breaker and a disconnecting switch located completely in an underground concrete oiltight vessel filled with oil and subdivided into individual compartments by horizontal insulating partition walls, said partition walls being disposed between the disconnecting switch and the circuit breaker.
- 30 2. A high-tension switch plant located completely in an underground oil-tight concrete vessel filled with oil and subdivided into individual compartments by vertical bulk-heads and by horizontal bulk-heads whereby the apparatus in the lower part of the vessel is isolated from the apparatus in the upper part of the vessel, the said bulk-heads having manholes establishing communication between neighboring compartments and covers for the manholes closing communication between the said compartments.
- 35 40 45

In testimony whereof, I have hereunto subscribed my name this tenth day of February, 1928, at Berlin-Siemensstadt, Germany.

HANS BARTHÉLT.
